(57) **CLAIM**

The ornamental design for a luminaire, as shown and described.

DESCRIPTION

FIG. 1 is a perspective view of a luminaire showing a first variant of the design;

FIG. 2 is a top view of the luminaire of FIG. 1;

FIG. 3 is a bottom view of the luminaire of FIG. 1;

FIG. 4 is a front view of the luminaire of FIG. 1;

FIG. 5 is a rear view of the luminaire of FIG. 1;

FIG. 6 is a right side view of the luminaire of FIG. 1;

FIG. 7 is a left side view of the luminaire of FIG. 1;

FIG. 8 is a perspective view of a luminaire showing a second variant of the design;

FIG. 9 is a top view of the luminaire of FIG. 8;

FIG. 10 is a bottom view of the luminaire of FIG. 8;

FIG. 11 is a front view of the luminaire of FIG. 8;

FIG. 12 is a rear view of the luminaire of FIG. 8;

FIG. 13 is a right side view of the luminaire of FIG. 8;

FIG. 14 is a left side view of the luminaire of FIG. 8;

FIG. 15 is a perspective view of a luminaire showing a third variant of the design;

FIG. 16 is a top view of the luminaire of FIG. 15;

FIG. 17 is a bottom view of the luminaire of FIG. 15;

FIG. 18 is a front view of the luminaire of FIG. 15;

FIG. 19 is a rear view of the luminaire of FIG. 15;

FIG. 20 is a right side view of the luminaire of FIG. 15;

FIG. 21 is a left side view of the luminaire of FIG. 15;

FIG. 22 is a perspective view of a luminaire showing a fourth variant of the design;

FIG. 23 is a top view of the luminaire of FIG. 22;

FIG. 24 is a bottom view of the luminaire of FIG. 22;

FIG. 25 is a front view of the luminaire of FIG. 22;

FIG. 26 is a rear view of the luminaire of FIG. 22;

FIG. 27 is a right side view of the luminaire of FIG. 22;

FIG. 28 is a left side view of the luminaire of FIG. 22;

FIG. 29 is a perspective view of a luminaire showing a fifth variant of the design;

FIG. 30 is a top view of the luminaire of FIG. 29;

FIG. 31 is a bottom view of the luminaire of FIG. 29;

FIG. 32 is a front view of the luminaire of FIG. 29;

FIG. 33 is a rear view of the luminaire of FIG. 29;

FIG. 34 is a right side view of the luminaire of FIG. 29;

FIG. 35 is a left side view of the luminaire of FIG. 29;

FIG. 36 is a perspective view of a luminaire showing a sixth variant of the design;

FIG. 37 is a top view of the luminaire of FIG. 36;

FIG. 38 is a bottom view of the luminaire of FIG. 36;
FIG. 39 is a front view of the luminaire of FIG. 36;
FIG. 40 is a rear view of the luminaire of FIG. 36;
FIG. 41 is a right side view of the luminaire of FIG. 36;
FIG. 42 is a left side view of the luminaire of FIG. 36;
FIG. 43 is a perspective view of a luminaire showing a
seventh variant of the design;
FIG. 44 is a top view of the luminaire of FIG. 43;
FIG. 45 is a bottom view of the luminaire of FIG. 43;
FIG. 46 is a front view of the luminaire of FIG. 43;
FIG. 47 is a rear view of the luminaire of FIG. 43;
FIG. 48 is a right side view of the luminaire of FIG. 43;
FIG. 49 is a left side view of the luminaire of FIG. 43;
FIG. 50 is a perspective view of a luminaire showing an
eighth variant of the design;
FIG. 51 is a top view of the luminaire of FIG. 50;
FIG. 52 is a bottom view of the luminaire of FIG. 50;
FIG. 53 is a front view of the luminaire of FIG. 50;
FIG. 54 is a rear view of the luminaire of FIG. 50;
FIG. 55 is a right side view of the luminaire of FIG. 50; and,
FIG. 56 is a left side view of the luminaire of FIG. 50.
The portions of the luminaire shown in broken lines form no
part of the design. The thin diagonal lines on the inner and
outer side walls of the luminaire represent translucency.
